UNITED STATES PATENT OFFICE.

JOSEPH P. ROBERTS, OF BELL, FLORIDA.

INTERNAL-COMBUSTION ENGINE.

1,103,842.

Specification of Letters Patent. Patented July 14, 1914.

Application filed December 18, 1912. Serial No. 737,473.

To all whom it may concern:

Be it known that I, JOSEPH P. ROBERTS, a citizen of the United States, residing at Bell, in the county of Alachua and State of Florida, have invented new and useful Improvements in Internal-Combustion Engines, of which the following is a specification.

This invention relates to internal combustion engines, the object in view being to provide a simple, reliable and noiseless valve mechanism for delivering charges of gas to the combustion space of each cylinder and completely exhausting the burnt gases therefrom in each complete cycle of movement.

With the above and other objects in view, the invention consists in the construction, combination and arrangement of parts, as will be hereinafter more fully described, illustrated in the accompanying drawings and pointed out in the claims hereunto appended.

In the accompanying drawings:—Figure 1 is a diametrical section through the valve seat base and casing. Fig. 2 is a section taken at right angles to Fig. 1. Fig. 3 is a perspective view of the valve seat base. Fig. 4 is a similar view of the valve seat sections. Fig. 5 is a similar view of the valve. Fig. 6 is a similar view of the expansion ring.

Referring to the drawings 1 designates a cylinder wall, 2 the valve casing and 3 the valve shaft.

In order to admit gas to the interior of the cylinder 1, the latter is provided with a port 41.

The valve comprises a valve seat base 43 which is stationary and substantially disk-shaped and provided with a port 44 through the same, adapted to have coupled thereto either a branch of the intake or exhaust manifold, as the case may be. The disk-shaped base is also provided with substantially semi-circular grooves 45 in which are received the circumferential flanges 46 of a diametrically divided or split valve seat, the two semi-cylindrical sections of which are designated 47. These valve seat sections 47 are secured to the valve seat base by means of semi-circular retainers 48 fastened by screws 49 or their equivalent to the base 43. While these retainers 48 confine the flanges 46 of the valve seat sections in the grooves 45, they admit of a sufficient amount of movement of the valve seat sections to

permit the same to be expanded into contact with the surrounding valve hereinafter described. The valve seat sections 47 are also cut away to form a gas port 50 adapted during each revolution of the valve shaft to register with port 41.

Within the valve seat is arranged an expansion spring ring 52 which is divided, as shown at 53 and provided with interfitting 65 and overlapping tongues and grooves 54. This expansion ring is also provided with a gas port 55 which is maintained in alignment with the port 50 in the valve seat. Extending around the valve seat is a cylindrical valve 56 which is provided in its cylindrical wall with a gas port 57 adapted in each revolution of the valve shaft to register with the ports 50 and 55 hereinabove referred to. This valve is closed at one side 70 by an end wall or web 58 and the latter is formed with a hole 59 to receive the valve shaft 3 and also a keyway 60 adapting said valve to be keyed to the valve shaft so as to rotate therewith. It will now be understood that the expansion ring 52 exerts an outward pressure from within and against the valve seat sections 47, causing the latter to bear snugly against the interior of the valve 56, thus preventing leakage of gas. 80 A spring 61 presses against the outside of the valve 56 so as to hold the same against the valve seat base and in proper relation to the valve seat.

By the means hereinbefore described, high maximum efficiency and power of the engine is obtained without any unnecessary complication and a practically noiseless motor results in view of the fact that all poppet valves are dispensed with and rotary valves 95 substituted therefor.

The silent action is further enhanced by providing an oil trough 70 in the bottom of each valve casing 2 in which the lower portion of the valve revolves, thus keeping all 100 parts of the valve in a perfectly lubricated condition.

I claim:

1. Valve mechanism for internal combustion engines embodying a rotary valve shaft, 105 a stationary ported valve seat base, a ported cylindrical valve seat thereon, and a ported cylindrical valve fast on the rotary valve shaft and working in contact with the valve seat.

2. Valve mechanism for internal combustion engines embodying a rotary valve shaft,

a stationary ported valve seat base, a ported cylindrical expansion valve seat thereon, and a ported cylindrical valve fast on the rotary valve shaft and working in contact with the valve seat.

3. Valve mechanism for internal combustion engines embodying a rotary valve shaft, a stationary ported valve seat base, a ported cylindrical valve seat thereon, and a ported cylindrical valve fast on the rotary valve shaft and encircling and working in contact with the valve seat.

4. Valve mechanism for internal combustion engines embodying a rotary valve shaft, a stationary ported valve seat base, a ported cylindrical valve seat thereon, a ported cylindrical valve fast on the rotary valve shaft and working in contact with the valve seat, and a spring holding the valve against the valve seat.

5. Valve mechanism for internal combustion engines embodying a rotary valve shaft, a stationary ported valve seat base, a divided and ported cylindrical valve seat thereon, and a ported cylindrical valve fast on the rotary valve shaft and working in contact with the valve seat.

6. Valve mechanism for internal combustion engines embodying a rotary valve shaft, a stationary ported valve seat base, a ported cylindrical valve seat thereon, a ported cylindrical valve fast on the rotary valve shaft and working in contact with the valve seat, and an expansion spring within said seat.

35 7. Valve mechanism for internal combus-

tion engines embodying a rotary valve shaft, a stationary disk-shaped valve seat base provided with a gas port and arcuate grooves, a sectional cylindrical valve seat seated in said grooves and provided with a gas port, 40 a cylindrical valve surrounding said seat and fast on the rotary valve shaft, and means for expanding the valve seat into contact with the valve.

8. Valve mechanism for internal combustion engines embodying a rotary valve shaft, a stationary disk-shaped valve seat base provided with a gas port and arcuate grooves, a sectional cylindrical valve seat seated in said grooves and provided with a gas port, 45 a cylindrical valve surrounding said seat and fast on the rotary valve shaft, and a split expansion ring within the valve seat provided with a gas port which registers with the port in the valve seat. 55

9. Valve mechanism for internal combustion engines embodying a rotary valve shaft, a stationary ported valve seat base, a ported cylindrical valve seat thereon, a ported cylindrical valve fast on the rotary valve shaft 60 and working in contact with the valve seat, and an oil reservoir in the bottom of the valve casing in which the valve revolves.

In testimony whereof I affix my signature
valve casing in which the valve revolves.
